ATTORNEY

UNITED STATES PATENT OFFICE.

GIDEON SIBLEY, OF PHILADELPHIA, PENNSYLVANIA.

BACK-REST FOR DENTAL CHAIRS.

SPECIFICATION forming part of Letters Patent No. 694,683, dated March 4, 1902.

Application filed May 29, 1900. Serial No. 18,366. (No model.)

To all whom it may concern:

Be it known that I, GIDEON SIBLEY, a citizen of the United States, residing in the city and county of Philadelphia and State of Pennsylvania, have invented certain new and useful Improvements in Back-Rests for Dental Chairs, of which the following is a full, clear, and exact description, reference being had to the accompanying drawings, forming a part 10 of this specification.

This invention relates to the back-rests of dental and other chairs, my object herein being to provide, first, a simple and efficient means whereby the back-frame may be locked 15 in different positions of angular adjustment in respect to the seat-section, and, secondly, an improved construction whereby the back-slide may be locked in predetermined positions of longitudinal adjustment on said 20 frame, as will be hereinafter described and claimed.

In the drawings, Figure 1 is a sectional side elevation of a portion of a chair embodying my invention. Fig. 2 is a front elevation, 25 partially in section, of the back-frame, its supporting-bars, and the locking devices, the back-rest proper being removed. Fig. 3 is a transverse section enlarged as on the line 3 3 of Fig. 2. Fig. 4 is a similar section as on the 30 line 4 4 of Fig. 1.

A is the seat-base; B, the back-frame; C, the back-slide, and D the rest or cushion. The back-frame is provided at its lower end with lateral lugs b, which are hingedly connected with lugs a on the seat-base, so that the said frame, with its appurtenances, may be swung backward and forward, as desired. 35 Pivoted to the rear of the said base are the lower ends of two bars b' b'', which extending 40 freely into longitudinal pockets or guideways b''' in the back-frame permit the adjustment of the latter, yet upon the clamping together of the bars and frame sustain the frame at a predetermined position of angular adjustment 45 in respect to the seat-section.

At the lower end of the back-frame in the space between the bars b' b'' are affixed two parallel studs e e', on one of which is very loosely mounted a roller E, that takes against 50 the opposing edges of the adjacent bar b', while on the other stud is likewise loosely mounted a cam E', which acts upon said roller

and upon the opposing edge of the bar b''. (See Fig. 3.) Formed on or affixed to this cam is a laterally-extending arm e'', which passes through an aperture e''' in the back-frame and is pivotally connected with a collar e'' on a vertically-movable rod e'', fitted within said frame. This rod is provided at its respective ends with exteriorly-projecting 60 knobs e'', by means of which the rod may be manipulated. Encircling the rod is a spring e'', which bearing upon the collar e'' and a shoulder e''' in the frame tends to maintain the rod normally depressed. The construction of the cam is such that when the rod is thus depressed the cam bears against the bar b'' and presses the roller against the bar b', in consequence of which the weight of the back-frame and its connections causes the 70 cam and roller to turn in opposite directions to each other against the opposing bars, the cam thus biting and binding against the roller and, perforce, effecting the clamping of the bars fixedly to the back-frame. By the act 75 of raising the rod against the compression of the spring the clamping action of the cam and roller is overcome, thus permitting the requisite adjustment of the back-frame. When the rod is released, the cam and roller 80 automatically resume their normal position to insure the clamping of the back-frame in place.

The slide C is fitted to longitudinal guideways b'' in the back-frame, so as to be movable 85 up and down therein, and it is provided with a projection c, which extends through a longitudinal slot b''' in said frame. Pivoted to this projection is a cam-lever F, the cam portion f of which embraces the outer end of the projection and acts against the back-frame, so that the weight of the latter tends to turn the cam, and thus effect the clamping of the slide in a predetermined position of vertical adjustment 90 on said frame. On the lever is a lug f', 95 against which bears the outer end of a spring f'', seated in a socket in the projection, the pressure of the spring tending to maintain the cam-lever normally in clamping position. By slightly raising the arm of the lever against 100 the stress of the spring the slide is unclamped to permit the requisite adjustment thereof. Upon the release of the lever it will automatically resume its normal position to effect the

clamping of the slide in the desired position of adjustment.

The cushion or rest D is pivoted at or near its upper end to the slide as usual, so that it 5 may be swung to and from the same, and is provided with a dog or dogs d, adapted to coact with a rack or racks d' on said slide for the purpose of supporting the cushion or rest at the proper angle with respect to the slide.

10 I claim—

1. In a chair, the combination with the seat and the swinging back-frame, of the supporting-bar extending into said frame, a device in said frame movable against the bar, a cam in said frame adapted to act upon said device to clamp it against the bar, said device being interposed between the cam and the wall of said frame, and means for operating said cam, substantially as described.

20 2. In a chair, the combination with the seat and the swinging back-frame, of the supporting-bar extending into said frame, a device in said frame movable against the bar, a cam in said frame adapted to act upon said device

25 to clamp it against the bar, and means for maintaining said cam normally in contact with said device, substantially as described.

3. In a chair, the combination with the seat and the swinging back-frame, of the supporting-bar extending into said frame, a roller in said frame adapted to coact with said bar, a cam in said frame adapted to act upon said roller to clamp it against the bar, and means for operating said cam, substantially as described.

35 4. In a chair, the combination with the seat and the swinging back-frame, of the supporting-bars extending into said frame, the coacting roller and cam engaging the respective bars, and means for operating said cam, substantially as described.

40 5. In a chair, the combination with the seat and the swinging back-frame, of the supporting-bars extending into said frame, the coacting roller and cam engaging the respective bars, and means for maintaining said cam and

roller normally in contact with each other and with said bars, substantially as described.

6. In a chair, the combination with the seat and the swinging back-frame, of the supporting-bars extending into said frame, the parallel studs affixed to said frame between the bars, a roller and a cam loosely mounted on the respective studs, and means whereby said cam and roller are normally maintained in 55 contact with each other and with the respective bars, substantially as described.

7. In a chair, the combination with the seat and the swinging back-frame, of the supporting-bars extending into said frame, the parallel studs affixed to said frame between the bars, a roller and a cam loosely mounted on the respective studs, an arm on said cam, a rod connected therewith, and a spring acting upon said rod to maintain the same normally 65 in such position that the said roller and cam are held yieldingly in contact with each other and with the respective bars, substantially as described.

8. In a chair, the combination with the back-frame, and the slide thereon, of the cam-lever mounted on said slide, means whereby the cam-head of the lever is maintained normally in contact with said frame, and means exteriorly of the frame for operating said cam- 75 lever, substantially as described.

9. In a chair, the combination with the longitudinally-slotted back-frame and the slide thereon provided with a projection extending through the slot in said back, of the cam-lever fulcrumed on said projection, and a spring tending normally to maintain said lever in contact with the frame, substantially as described.

95 In testimony whereof I have hereunto affixed my signature in the presence of two subscribing witnesses.

GIDEON SIBLEY.
